APPARATUS FOR PRESSING RECORDS

Thomas F. Stacy, Piqua, Ohio, assignor to The French Oil Mill Machinery Company, Piqua, Ohio

Application March 22, 1945, Serial No. 584,192

5 Claims. (Cl. 18—16)

1

This invention relates to record presses and particularly to the mechanism by which a cycle of operation of the press is carried out automatically, and to an improved method of operating such a press.

In record presses where the head tilts into and out of pressing position, the head has considerable mass and consequently inertia. It is desirable that the closing and opening movements of the head be rapid, in order that the time required for each operation of the press be a minimum, which results in increased output of the press. If the head moves quickly, there is danger of shock in the press structure due to inertia if the head is stopped suddenly, and to start a substantial mass in operation suddenly or to stop it suddenly requires considerable force, and hence considerable available operating power. The sequence of operations or steps in a complete pressing cycle should be in a particular order, and the time between successive operations should be a minimum, so that the time required for a complete operation of the press may be a minimum. Heretofore the various steps in the operation of a press have been under the control of a timer, but it has been necessary to allow adequate time for each operation or step before the next step is initiated, and because of this the steps cannot proceed as rapidly in the sequence as might otherwise be possible. If adequate time was not allowed for each operation to be completed before the next one was initiated, a second step might be initiated before the next preceding one was fully completed, possibly resulting in wrecking or seriously damaging the press. For example, if the locking bars were unable to move fully into locking position before full pressure was applied to the platen, serious injury to the press might result.

An object of this invention is to provide an improved method of operating a record press, and an improved control apparatus for the press, through which the time required for a complete cycle of operation of the press may be reduced to a minimum without danger of injury to the press through incomplete performance of any step before a succeeding step is initiated, and which will be relatively simple, practical and dependable.

Another object of the invention is to provide an improved method of operating a record press, with which the different operating steps may follow one another safely and rapidly in proper sequence, which will require a minimum of changes in the operating mechanism of a record

2

press, and with which the movement of the tilting head into and out of pressing position may be rapid but without shock, and require a minimum of operating power.

5 Another object of the invention is to provide an improved apparatus for operating a record press, with which the operating steps may safely be caused to follow one another in rapid sequence, with a minimum of time delay between 10 successive steps, which will be automatic in action once a cycle has been initiated, which will require a minimum of servicing, which will not greatly increase the space occupied by the press and its controls, with which the sequence of 15 steps will be carried out in their reverse order when the pressing operation has been completed, and which will be relatively simple, compact and inexpensive.

Another object of the invention is to provide 20 improved means for tilting the head with which the initial and final movements will be relatively slow, but rapid in the intermediate movements, so that the tilting will be rapid but free from shock, and which will require a minimum size 25 of operating motor for tilting the head.

Various other objects and advantages will be apparent from the following description of one embodiment of the invention, and the novel features will be particularly pointed out hereinafter 30 in connection with the appended claims.

In the accompanying drawings:

Fig. 1 is a side elevation, partly in section, of a record press with a tilting head constructed in accordance with this invention, the head being 35 shown in pressing position after a pressing operation and just as the head is about to be unlocked;

Fig. 2 is a front elevation of the same;

Fig. 3 is a rear elevation of the same with certain parts broken away to show interior details 40 of construction of some of the parts;

Fig. 4 is a plan of the same; and

Fig. 5 is a schematic diagram of the controls 45 that may be employed with such a press in accordance with this invention.

In the illustrated embodiment of the invention the press includes a frame 1 having upstanding, spaced parallel sides 2 and 3, and a pressing head 4 pivoted on its opposite side edges by trunnions 50 or pivots 5 to the side members 2 and 3. This head 4 extends forwardly from the pivots 5 between the upright sides 2 and 3 and is free to tilt upwardly and rearwardly from pressing position about the axis of pivots 5. A counter 55 weight 6 mounted on the rear end of the head

3 beyond the pivots 5 balances the head and decreases the power required to tilt the head from its horizontal pressing position, shown in full lines in Fig. 1, to an inclined position shown by the dash lines A, in Fig. 1. A link 7 is pivoted by pin 8 to the rear end portion of the head 4 in a slot therein, and at its other end is pivotally connected by a crank pin 9 to a crank arm 10 which is fixed on a shaft 11. The shaft 11 is suitably mounted for rotation in the base of the frame 1 of the press, and it also has fixed thereon a gear or pinion 12 so that the pinion 12 and crank arm 10 will both rotate with the shaft 11.

Mounted for reciprocation on a surface 13 of the base of frame 1 is a rack bar 14 having its teeth meshing with the teeth of the pinion 12. When the rack bar 14 is reciprocated, it will rock the crank arm back and forth. The rack bar 14 is connected at one end to a piston rod 15 that extends into an operating cylinder 16 and within said cylinder carries a piston head, so as to form with the cylinder 16 a double acting, fluid operated motor. When the piston rod 15 is at one limit of its movement, such as its advance movement, as shown in Fig. 1, the crank arm 10 and the connecting rod or link 7 will be in approximate alinement, that is, the crank pin 9 will be in approximate dead-center position, with the head 4 in its horizontal, pressing position. When the piston rod 15 is retracted into its cylinder 16, its rack bar will rotate the crank arm 10 counter-clockwise in Fig. 1, and through the link 7 will tilt the head 4 into the inclined position shown by the dash line A in Fig. 1. When the piston rod 15 is again advanced, it will return the crank arm 10 to the position shown in full lines in Fig. 1, and thus tilt the head 4 into the pressing position.

The side frame member 2, at its upper end, has a pair of lugs 17 (Figs. 2 to 4) spaced apart forwardly and rearwardly, and the side frame member 3 has similar lugs 18 spaced apart forwardly and rearwardly. The lugs 17 project towards the opposite lugs 18, the forward lugs 17 and 18 being alined with each other transversely of the press, and the rear lugs 17 and 18 being similarly alined with each other. The head 4 is narrow enough to pass between the lugs 17 and 18 when the head 4 is tilted. The forward end of head 4 (Fig. 1) mounts a pair of locking members 19 and 20 for sliding movement forwardly and rearwardly, and these members are connected to each other in spaced relation by spacing rods 21 carrying nuts 22 on the ends of the rods which clamp between them opposite faces of the members. This spaces the members on the rods. Each of these members 19 and 20 has a width, considered from side to side of the machine, sufficient to extend beneath the oppositely disposed and alined lugs 17 and 18. They have depths from front to rear such that when the head 4 is tilted into and out of the horizontal position, while the members 19 and 20 are in the dash line positions shown by dash lines B in Fig. 1, they will clear the lugs 17 and 18.

When the head 4 is horizontal, as shown in the full line position in Fig. 1, the members 19 and 20 may be moved forwardly as a unit to engage beneath lugs 17 and 18, and lock the head 4 in its horizontal, pressing position and against upward and rearward tilting. Wear shoes 23 of hardened metal may be secured on the upper surfaces of the members 19 and 20 to engage beneath the lugs 17 and 18. Stops 24 (Fig. 2) are disposed on the side members 2 and 3 to

limit the movement of the head 4 beyond a horizontal position, and the walls of these stops 24 may have beveled cam surfaces 25, Fig. 2, which are downwardly convergent, and which at their wider, upper portions receive the edges of the head 4 and guide the head 4 downwardly so as to center it horizontally in proper position above the platen 26. It will be understood that the record dies may be carried on the head 4 and platen 26 as usual in record presses. The stops 24 and the head 4 may have hardened strike plates 27 and 28 respectively, at opposite sides of the press which accurately limit the movement of the plate 4 as it moves into pressing position.

A piston 29, Figs. 1 and 4, operates in a cylinder 30 and with it forms a double-acting, fluid actuated motor, and the free or outer end of the piston 29 is coupled to the rear locking member 20. The cylinder 30 is mounted on the upper face of the head 4, and it serves to reciprocate the locking members 19 and 20 forwardly into locking position, and rearwardly into unlocked position, which positions are determined by engagement of the members 19 and 20 with opposite ends of limit stop C (Fig. 1). The platen 26 is reciprocated upwardly by a ram or piston 31, Fig. 5, which operates in a cylinder 32. The admission of fluid to, and its release from the cylinder 32 is controlled by a suitable reversing valve 33, Fig. 5, which is pilot operated by an air motor 34. Operating fluid, such as a hydraulic liquid, is admitted to the valve 33 through a pipe 35 running from a source of operating fluid under pressure, and a pipe 36 connects the valve to the reservoir or exhaust. When the air motor 34 is operated in one direction, it connects the pipe 35 to the cylinder 32, and when in the other direction it connects the exhaust pipe 36 to the cylinder and disconnects the cylinder 32 from pipe 35.

A guard or gate in the nature of a plate 37 (Figs. 1 and 4) is slidably mounted in guides 38 at the forward face of the frame, for movement vertically in any suitable manner such as by a piston 39 operating in a cylinder 40 and forming a double-acting, fluid actuated motor. In the example illustrated, the piston 39 is connected to a plate 41 which is guided vertically in one of the guides 38, and this plate 41 rotatably mounts a pinion 42. This pinion 42 meshes with the teeth of a stationary rack 43 which is mounted on the guide 38, and also meshes with the teeth of a rack 44 which is fixed to the gate 37. The racks 43 and 44 extend vertically in parallel relation, and when the gear 42 is shifted bodily in a vertical direction, it will roll along the rack 43 and cause a vertical movement of the rack 44 in the same vertical direction and thus elevate the gate 37 into a protective position in front of the press where it prevents access to the space between the platen 26 and the head 4. When the piston 39 is retracted, it lowers the pinion 42 and thus similarly lowers the rack 44 and gate 37. Referring now particularly to Fig. 5, the operating system with controls is illustrated diagrammatically. The hydraulic motors having the cylinders 16, 30 and 40 are shown as of the double acting type, operated by a fluid under pressure from a suitable source, such as compressed air under a relatively high or substantial pressure, which is supplied through a pipe 45. The pipe 45 is connected to a pilot operated, 4-way reversing valve 46 which is connected by pipes 47 and 48 to opposite ends of the cylinder 30. This valve 46 has

exhaust ports 49. Valves of this type are well known in the art, and for that reason they have been shown only diagrammatically. They have a valve element which, when moved endwise, connects the pipes 47 and 48 alternately to the pipe 45, and the pipe 47 or 48 which is not connected at any time to the pipe 45 is automatically connected to one of the exhaust ports 49. The pilot chamber in valve 46 is operated by fluid pressure supplied by a pipe 50 in a manner which will be explained later.

Similarly the pipe 45 is connected to a pilot operated, 4-way, reversing valve 51 which is connected by pipes 52 and 53 to opposite ends of the cylinder 46. The valve 51 has exhaust ports 54, and when the valve element of this valve is operated, it connects the pipe 45 alternately to the pipes 52 and 53, and vents whichever of those pipes is then disconnected from pipe 45. The valve chamber of that valve is supplied with operating fluid through a pipe 55 in a manner which will be explained later. The pipe 45 is also connected to another pilot operated, 4-way reversing valve 56 which is connected by pipes 57 and 58 to opposite ends of the cylinder 46, so that when the valve element of valve 56 is operated, it connects the pipe 45 alternately to the pipes 57 and 58 and vents to exhaust ports 59, whichever of those pipes 57 or 58 is then disconnected from the pipe 45. The pilot chamber of valve 56 is supplied with operating fluid through a pipe 60 in a manner which will be explained later. Pipe 45 is also connected, through a pressure reducing valve 61, to a low pressure line 62 which supplies the operating fluid or air for the various pilot chambers.

The material from which records are made is usually a thermo-plastic material which is molded while soft, in dies, and then chilled while under pressure in the dies, so that it will retain its molded form. Accordingly the dies must be heated to soften the molding material and keep it soft and moldable while it is being pressed, and after it has been pressed, the steam must be disconnected and the die cooled, such as by circulation of a chilling fluid through the dies, in order to set or harden the pressed and molded material. For this purpose a suitable timer is employed for controlling the duration of the cycle, and the admission of steam and water to the dies for heating and chilling them. It also controls the valve that regulates the exhaust from the steam plates that may be either open to a waste-line or to a trap line, so that the condensate can be returned to a hot well.

One example of such a suitable time controller, which has been found satisfactory for this purpose is illustrated diagrammatically in Fig. 5, and it is obtainable in the open market under the trade name "Flex-o-Timer" or time cycle controller, manufactured and sold by Taylor Instrument Companies of Rochester, New York. It is disclosed in Bulletin #98,154, June, 1940 edition of the Taylor Instrument Companies, and also is disclosed in U. S. Patent No. 2,272,237 of February 10, 1942, to which reference may be had for a more complete disclosure of a suitable timer. Such a timer has a series of air valves 63, 64, 65 and 66. The air valve 63, when operated, serves to connect the pilot line 60 alternately to the low pressure air line 62 and to an exhaust port 67. The valves 64, 65 and 66 are similar valves that control the water, steam and trap or by-pass lines in a similar manner through pilot operated valves. One example of such a

valve is disclosed in U. S. Patent No. 2,261,827 of November 4, 1941.

To initiate an operation of a press, the operator will operate a push button in the timer, not shown, which starts the timer in operation for a cycle, and immediately the timer operates the valve 63 to connect the pipe 60 to the low pressure supply line 62. It will be understood that previously, while the timer was idle, the pilot pipe 60 was connected by valve 63 to the exhaust port 67. When the timer starts, it controls the valves 63, 64, 65 and 66 and causes their operation in a predetermined manner which need not be further considered in connection with this invention, except that the valve 63 will be held closed for the desired period of operation of the cycle, and then when the timer times out or finishes its cycle, the valve 63 will disconnect pipe 60 from the air supply line 62 and connect it to port 67.

When compressed air is supplied to the pipe 60, it causes an operation of valve 56 to establish the flow connections therethrough as shown by the dash lines in Fig. 5, in which the air line 45 is connected to the lower end of the cylinder 40, which causes an advance of the gate piston 39 so as to carry the gate into protective position, that is, its elevated position in this type of press. The continuance of pressure in the pilot line 60 will serve to hold the gate in its protective position until the timer times out and valve 63 vents the pipe 60.

The pilot line 50 which leads to the valve 46 is connected through a 2-way valve 68 to a pipe 69 leading to another 2-way valve 70. The valve 70 is connected by a pipe 71 to a valve 72, and also to the air supply line 62. The valve 72 is also a 2-way valve which, when operated, connects the pipe 71 alternately to an exhaust port 73 and to a pipe 74 which is connected to the pilot pipe 60. The valve 72 is controlled by the gate or the gate piston 39, as the gate moves into or leaves its full protective position. In the diagram of Fig. 5, the gate piston 39 of the gate rocks a bell crank lever 75 against the action of a spring, and the valve 72 is spring operated into one connecting position when the bell crank releases the valve, and is operated into its other connecting position when the bell crank 75 is released to the action of its own spring which overcomes the spring of the valve. The gate piston 39 may, however, operate the valve element of valve 72 directly, instead of through a bell crank. When the gate is lowered, the valve 72 is operated to connect the pipe 71 to the exhaust port 73, but when the gate approximately reaches its full protective position, it causes an operation of the valve 72 to connect the pipe 71 to the pipe 74.

The valve 70 has its movable valve element spring actuated in one direction and positively moved in the other direction by a lever 76 pivoted at 77, and disposed to be engaged and operated by the platen 26. When the platen 26 rises, it releases lever 76, and the latter releases the valve element of the valve 70, and that valve element is then moved into a position to connect the pipe 69 to the pipe 62. When the platen 26 descends and has about reached the end of its descent, it rocks lever 76 in a direction to cause an operation of valve 70 in a manner to connect the pipe 69 to the pipe 71.

The valve 68 is operated by a lever 78 pivoted at 79. Lever 78 is disposed to be operated by the head 4 as the head moves into its pressing

position, and when so operated, the lever 78 releases the valve element of valve 68, which is spring actuated into a position to connect the pipe 50 to the pipe 69. When the head 4 moves out of pressing position, it releases lever 78 and a spring 80, which is more powerful than the spring in the valve 68, operates the valve 68 to connect the pipe 50 to an exhaust port 81 instead of to the pipe 69.

Another 2-way valve 42 is disposed for operation by a lever 83 pivoted at 84, and this lever, in turn, is disposed for operation by the locking member 19 when that member moves into locking position on the head 4 while the latter is in pressing position. The valve 82 has its movable valve element pressed in one direction, and operated in the opposite direction by the lever 83. This valve serves to connect a pipe 85 from the air motor 34 alternately to a pipe 86 and to an exhaust port 87. The pipe 86 is connected to the pipe 71. When the valve 72 connects the pipes 71 and 74, such as when the gate is in its protective position, it also connects the pipe 86 from the valve 82 to the source of air from the timer valve 63.

A valve 88, similar to the valve 82, is also connected to the pipe 86. A pipe 89 connects another port of the valve 88 to the low pressure air line 62 before it reaches the timer valve 63. The valve 88 is also connected to the pipe 55 which leads to the pilot chamber of the head tilting, control valve 51. The valve 88 connects the pilot pipe 55 alternately with pipes 86 and 89. It is spring pressed in one direction and operated in the opposite direction by lever 90 pivoted at 91, and disposed for operation by the locking member 20 as the latter approaches its fully retracted or unlocked position. The valves 68, 70, 72, 82 and 88 may be of the type shown in said Patent No. 2,261,827.

In the operation of a press having these controls, a cycle of operation is initiated by operating the starting push button on the timer, not shown, but which is a part of the timer. The timer then begins its cycle of operation and immediately closes its valve 63 which previously had connected the pilot pipe 60 to the exhaust port 67. The valve 63, when operated by the timer, connects the low pressure air line 62 to the pilot line 60 which leads to the gate reversing valve 56, causing an operation of that valve to establish the flow connections shown by dash lines in Fig. 5. Air under high pressure from the line 45 then passes to the bottom of the cylinder 40, and causes an advance of the gate into protective position in front of the press. As the gate reaches or closely approaches its limit of movement in this manner, it causes an operation of the valve 72. When the gate was in its retracted position, the valve 72 connected pipe 71 to the exhaust, as shown by the dash line flow connection, but when the valve was caused to operate by the movement of the gate into protective position, it connects pipes 71 to 74.

At this time, the valve 82 connects the pilot pipe 85 to exhaust, since the locking mechanism is unlocked, but valve 88, which was operated by the locking member 20 at the end of the unlocking movement, connects the pilot pipe 55 to the pipe 86. Compressed air passing through timer valve 63 can therefore pass from the pipe 60 through pipe 74, valve 72, pipe 71, pipe 86, valve 88 and pipe 55 to the pilot cylinder of valve 51, and operate the valve 51 into a position to air flow therethrough, as shown by dash lines in Fig. 5. In that position it connects the high pressure air line 45

10 to the pipe 53, and causes a movement of the crank arm 10 from its inclined position shown by dash lines A in Fig. 1 into the dead-center position shown in Fig. 5 to lower the head 4 into pressing position, which is shown by the full lines in Fig. 1. When the head 4 was inclined or out of pressing position, the valve 68 connected the pipe 50 to exhaust port 81, and therefore no air would flow through pipe 71 beyond valve 70.

15 When the head 4 substantially reaches its pressing position, shown in Fig. 5, it causes an operation of valve 68 to change the flow from the dash line position in that valve to the full line position, and connects pipes 50 and 69. Low pressure air then is allowed to flow from timer valve 63 through pipes 60 and 74, through valve 72 to pipe 71, through valve 70, pipe 69, valve 68 and pipe 50 to the pilot chamber of reversing valve 46. Valve 46 is then operated into a position to cause flow therethrough in the directions shown by the dash lines in Fig. 5, which admits high pressure air from the supply line 45 to the pipe 47 and then to one end of the cylinder 30 where it causes an advance of the locking members 19 and 20 into the locking position shown in Fig. 5. At the beginning of this movement, the locking member 20 releases the lever 90, and this causes an operation of the tie in valve 88 to connect the pilot pipe 55 to the pipe 89, which directly connects the air line 62 to the pipe 55 irrespective of the timer valve 63, so that the air pressure will remain on the pilot cylinder of reversing valve 51 after the timer valve 63 has timed out.

20 When the locking member 19 approximately reaches its locking position, it operates lever 83, and through it, causes an operation of valve 82 to connect the pipe 85 to the pipe 86, as shown by the full lines in the valve in Fig. 5. Air from the timer 63 can then also pass through the pipes 60 and 74, valve 72, pipes 71 and 86, valve 82, and pipe 85 to the air motor 34. The air motor then operates valve 33 to cause fluid flow in the direction shown by the arrows in pipes 35 and 36 to deliver operating fluid under pressure to the hydraulic motor 32. This causes an advance of the ram 31 and platen 26 toward the pressing head 4. As soon as the platen 26 begins its advance, it releases lever 76, and this releases the valve 70 for operation into the full line flow position, shown in Fig. 5, where it connects the pipes 69 and 62. This connects the air line 62 through the valve 68 to the pilot chamber of the reversing valve 46, irrespective of the timer valve 63, so that after the timer times out, air will still be admitted to the pilot chamber of valve 46 to keep the locking members 19 and 20 in their advanced or locked position.

25 The pressing operation then continues, and at the conclusion of the cycle, as determined by the timer, the valve 63 is operated to disconnect the air line 62 from the pipe 60, and to vent the pipe 60 to the port 67. When the air is released from pilot pipe 60, reversing valve 56 automatically reverses by spring action, and admits fluid from the air line 45 to the upper end of the gate opening cylinder 40, and causes a retraction of the gate from its protective position. As soon as the gate begins its descent or retraction, valve 72 operates to vent the pipe 71 to exhaust (see dash line position), in addition to the venting of the pipe 74 through the pipe 60 to exhaust. This vents the pipe 86, and the latter, which is connected through valve 82 to pipe 85, vents the air motor 34, and thereupon reversing valve 33 causes a re-

traction of the ram 31 into the cylinder 32, and a retraction of the platen 26. During this retraction, the air pressure remains on the locking cylinder 30, and the head 4 remains locked.

When the platen 26 closely approaches its retracted position, it rocks lever 76, and thereby operates valve 70 to reconnect the pipe 69 to the pipe 71 and vent it through valve 72 to the exhaust port 73. Air then escapes from the pilot chamber of reversing valve 46, and the latter then reverses and delivers air, under pressure, to the opposite end of cylinder 30 which moves the locking members 19 and 20 out of locking position. At the beginning of this locking movement of members 19 and 20, lever 83 is released, which causes an operation of valve 82 to further vent pipes 85 from the air motor 34 directly through the exhaust port 81. When the locking member 20 has been fully retracted or unlocked, it operates lever 90, and through it, valve 88, to reconnect pipe 55 to the vented pipe 86 thereby venting pilot pipe 55.

When this happens, reversing valve 54 reverses by spring pressure, and air from high pressure line 45 is delivered through pipe 52 to the opposite end of cylinder 16 and retracts the rack 14, which rocks the crank arm 10 counter-clockwise in Fig. 5 to tilt the head 4 into an inclined position, shown by the dash lines A in Fig. 1. At the beginning of this tilting movement of the press head 4, the crank pin 9 in moving from its dead-center position to tilt the head 4, moves very slowly at the start, and then accelerates rapidly in a simple, harmonic movement. At the beginning of this tilting operation, head 4 releases lever 18, and this results in an operation of valve 68 to directly vent pipe 50 through the port 81, the flow being shown by the dash lines in valve 68, Fig. 5. It will be noted that with this crank action, the head 4 is thus moved into and out of pressing position with a simple harmonic motion which is very desirable and free of shocks in this type of press.

The parts thus all return to their normal, idle positions and remain there until a new cycle of operation is started by a reactivation of the timer, whereupon the same cycle of operation is repeated, as above explained. The operations of the valves 64, 65 and 66 are not explained because they are controlled by the timer and, per se, are no part of the present invention. It will also be noted that when a cycle of operation is initiated, it continues automatically, with the steps performed in proper sequence and each step controlled by a preceding step until the pressing operation is completed. When the timer times out to terminate this pressing operation, the press is automatically opened and the parts returned to their normal, idle positions by a reverse sequence of steps in the proper order.

It will be understood that various changes in the details and arrangements of parts, which have been herein described and illustrated in order to explain the nature of the invention, may be made by those skilled in the art within the principle and scope of the invention as expressed in the appended claims.

I claim:

1. In a record press of the type having a reciprocating platen, a head shiftable into and out of pressing position in which the pressing face is normal to the direction of movement of the platen, a gate movable into and out of a protective position relative to said head when in pressing position, power operated means for mov-

ing said head into and out of said positions, and means for locking said head in pressing position, that improvement in the control thereof which comprises the combination with said press of pilot controlled means for controlling the movements of said head into and out of pressing position, pilot controlled means for controlling the movements of said gate, a connection from a source of fluid under pressure to the pilot controlled means of said gate, a valve in said connection for controlling flow thereto, a second valve operated by said gate as said gate reaches protective position, a second pipe having said second valve in series therein and connected to said pipe leading from said first valve to said gate pilot controlled means, a fluid controlled pilot device for controlling the operation of said locking means and connected to said second pipe to receive fluid from said second valve when said gate is in protective position and initiate a locking operation of said head, a third valve in series in said second pipe normally venting said second pilot control means and disconnecting it from said second valve, but operable by said head, as said head moves into pressing position, to connect said second valve to said second pilot control means, whereby said locking operation will be deferred until said head has moved into pressing position, a fourth valve connected in said second pipe between said third valve and said second valve, and operable to connect said third valve alternately to said second valve and directly to said source of fluid pressure, and means controlled by the platen and operable into a position to connect said third valve directly to said fluid force while said platen is away from retracted position, whereby said gate may open after said platen has completed a pressing operation, and while fluid pressure remains on said second pilot control means.

2. In a record press of the type having a reciprocating platen, a head shiftable into and out of pressing position in which the pressing face is normal to the direction of movement of the platen, a gate movable into and out of protective position relative to said head when in pressing position, power operated means for moving said head into and out of said positions, and means for locking said head in pressing position, that improvement in the control thereof which comprises the combination with said press of pilot controlled means for controlling the movements of said head into and out of pressing position, pilot controlled means for controlling the movements of said gate, a connection from a source of fluid under pressure to the pilot controlled means of said gate, a valve in said connection for controlling flow thereto, a second valve operated by said gate as said gate reaches protective position, a second pipe having said second valve in series therein and connected to said pipe leading from said first valve to said gate pilot controlled means, a fluid controlled pilot device for controlling the operation of said locking means and connected to said second pipe to receive fluid from said second valve when said gate is in protective position and initiate a locking operation of said head, a third valve in series in said second pipe normally venting said second pilot control means and disconnecting it from said second valve, but operable by said head, as said head moves into pressing position, to connect said second valve to said second pilot control means, whereby said locking operation will be deferred until said head has moved into press-

ing position, a pilot controlled means governing the movement of said platen, a conduit connecting said third pilot controlled means to said second valve, a valve in said conduit operable to connect said third pilot control means alternately to said second valve and to exhaust, said valve in said conduit being normally in the position at which it connects said third pilot controlled means to exhaust, but caused to operate into its other position by said locking means as the latter completes its locking of said head in pressing position, whereby said platen will not start an advance movement until said head has been securely locked.

3. In a record press of the type having a press head mounted to swing into and out of a pressing position with respect to the movement of a pressing platen that is operated towards said head by a fluid actuated motor having a pilot operated controlling valve, a frame mounting said head and platen, and locking means for locking the free end of said head to said frame in pressing position, that improvement therein which comprises a fluid actuated motor for operating said locking means, a fluid actuated motor for operating said head into and out of pressing position, a gate movable into and out of protective position in front of said head and platen, a fluid actuated motor for operating said gate, a source of high pressure operating fluid connected to each of said motors, a pilot valve for the connection to each of said motors to control the activity of that motor, a source of low pressure operating fluid connected to each of said pilot valves, a timer in the connection to the controlling pilot valve of said gate operating motor for causing said gate motor to close the gate, means made effective by said gate when closed for connecting low pressure fluid from said timer to the pilot valve of said head locking motor to cause an operation of that motor to lock said head, means rendered effective by partial movement of said locking means towards locking position for connecting said source of fluid under low pressure to said pilot operated valve of said head swinging motor to cause movement of said head into pressing position, means including a valve operated by said head locking means when the locking has been complete for connecting low pressure fluid from said timer to the pilot control valve of said platen operating motor to cause a pressing advance of the platen, and valve means controlled by said platen after it begins its pressing operation for connecting said low pressure fluid directly to the control pilot valve of said head locking motor in shunt to said timer to maintain the locking of said head free of control by said timer, said timer, when it completes a timing operation, discontinuing connection of low pressure to the pilot valve controlling said gate operating motor to start the gate towards open position, said gate controlled means being effective upon the opening of the gate to release the fluid pressure on the pilot control valve of said platen operating motor and begin an opening of said press.

4. In a record press of the type having a press head mounted to swing into and out of a pressing position with respect to the movement of a pressing platen that is operated towards said head by a fluid actuated motor having a pilot operated controlling valve, a frame mounting said head and platen, and locking means for locking the free end of said head to said frame in pressing position, that improvement therein which com-

prises a fluid actuated motor for operating said locking means, a fluid actuated motor for operating said head into and out of pressing position, a gate movable into and out of protective position in front of said head and platen, a fluid actuated motor for operating said gate, a source of high pressure operating fluid connected to each of said motors, a pilot valve for the connection to each of said motors to control the activity of that motor, a source of low pressure operating fluid connected to each of said pilot valves, a timer in the connection to the controlling pilot valve of said gate operating motor for causing said gate motor to close the gate, means made effective by said gate when closed for connecting low pressure fluid from said timer to the pilot valve of said head swinging motor and cause that motor to move said head into pressing position after said gate has closed, means including a valve operated by said head when it reaches closed position for connecting said low pressure fluid through that valve from the timer to the pilot valve of said head locking motor to cause an operation of that motor to lock said head, means rendered effective by partial movement of said locking means towards locking position for connecting said source of fluid under low pressure to said pilot operated valve of said head swinging motor to cause movement of said head into pressing position, means including a valve operated by said head locking means when the locking has been complete for connecting low pressure fluid from said timer to the pilot control valve of said platen operating motor to cause a pressing advance of the platen, and valve means controlled by said platen after it begins its pressing operation for connecting said low pressure fluid directly to the control pilot valve of said head locking motor in shunt to said timer to maintain the locking of said head free of control by said timer, said timer, when it completes a timing operation, discontinuing connection of low pressure to the pilot valve controlling said gate operating motor to start the gate towards open position, said gate controlled means being effective upon the opening of the gate to release the fluid pressure on the pilot control valve of said platen operating motor and begin an opening of said press.

5. In a record press of the type having a press head mounted to swing into and out of a pressing position with respect to the movement of a pressing platen that is operated towards said head by a fluid actuated motor having a pilot operated controlling valve, a frame mounting said head and platen, and locking means for locking the free end of said head to said frame in pressing position, that improvement therein which comprises a timer, means actuated by said timer for causing said gate to close, means activated by said gate while in closed position for causing said head to swing into pressing position, means activated by said head as it reaches closed position for causing said locking means to lock said head in pressing position, means activated by said locking means as it begins a locking movement for removing said head swinging means from the control of said timer, means activated by said locking means as it locks said head for causing a pressing movement of said platen towards said head, and means activated by said platen after it begins its pressing movement for removing said locking means from the control of said timer, said timer being effective at the end of a period of time for which it is set, to cause an

opening movement of said gate, then a retraction of said platen, then an unlocking of said head, then a return of the control of said lock to said timer, then a return of said head movement control to said timer, and then a movement of said head from pressing position to complete a cycle of operation.

THOMAS F. STACY.
